UNITED STATES PATENT OFFICE

CHARLES W. MCKINLEY, OF TOLEDO, OHIO, ASSIGNOR TO THE TILLOTSON MANUFACTURING COMPANY, OF TOLEDO, OHIO, A CORPORATION OF OHIO

CARBURETOR

Application filed May 27, 1924. Serial No. 716,091.

This invention relates to carburetors and, more particularly, to a carburetor in which a temporarily increased supply of motor fuel is automatically provided as the throttle valve is opened to accelerate or speed up the motor.

In the usual types of commercial carburetors, a current of air is drawn through the carburetor at a rate controlled by a throttle valve, and gasoline or other motor fuel is drawn into the flowing current of air in proportion to the rate of flow of the air therethrough, the quantity of fuel supplied being approximately proportional to the quantity of air being drawn through the carburetor and controlled by the position of the throttle valve. As the throttle is opened, the engine supplied with fuel from the carburetor is speeded up, the carburetor being so designed that the rate of fuel supply is about sufficient to supply the demand of the motor at the speeds corresponding to the various throttle openings. As the engine is increasing from a lower to a higher speed with the opening of the throttle, a somewhat richer mixture is required to bring the engine, and the mechanism driven therefrom, to the required speed than is required to maintain them running at the higher speed. Accordingly, a somewhat larger quantity of fuel is required for a short period of time while the engine is accelerating and speeding up.

An object of the present invention is to fulfill this requirement by automatically supplying an additional or auxiliary charge of fuel during the acceleration of the engine from low to high speed.

Another object of the invention is to provide a carburetor having an additional or auxiliary fuel supply for acceleration in which the feeding of additional fuel is distributed over a period of time and in which a closing of the throttle within this time will end the further feeding of this additional fuel.

A further object of the invention is to provide an accelerating fuel supply responsive to the opening of the throttle, in which the flow of fuel to the mixing passage from

such supply is controlled by the suction existing in the mixing passage.

A further object of the invention is to provide an accelerating fuel supply which is automatically cut off by the closing of the throttle.

A further object of the invention is to provide a carburetor having an accelerating nozzle supplied from a well into which fuel is discharged automatically upon the opening of the throttle.

Another object of the invention is to provide an accelerating pump actuated by the throttle valve and having means for preventing the trapping of air in the pump.

Further objects, and objects relating to details and economies of construction and operation will definitely appear from the detailed description to follow. In one instance, I have accomplished the objects of my invention by the devices and means described in the following specification. My invention is clearly defined and pointed out in the appended claims. A structure constituting a preferred embodiment of my invention is illustrated in the accompanying drawings forming a part of this specification, in which

Fig. 1 is a plan view of a carburetor embodying one form of my invention,

Fig. 2 is a sectional view of the carburetor, taken on line 2-2 of Fig. 1,

Fig. 3 is an end view of the carburetor, looking from the left of Fig. 2, portions being broken away to show the interior construction, and,

Fig. 4 is a side view, partly in section, of the carburetor, taken on line 4-4 of Fig. 1.

In the drawings, the same reference numerals refer to the same parts throughout the several views, and the sectional views are taken looking in the direction of the arrows at the ends of the section lines.

In general, my invention consists in providing an accelerating well or reservoir, from which fuel is delivered to the mixing passage to supply the rich mixture required for acceleration, said well being automatically supplied with a charge of fuel upon the opening of the throttle. I propose to

provide a pump which is actuated by the throttle valve, or the operating connections therefor, and which injects a charge of fuel into such accelerating well from which it flows through a jet, nozzle or orifice into the mixing passage. I propose to provide a well of such dimensions as to maintain the flow to the mixing passage for a period after the opening of the throttle, provided the throttle is not closed during that period. I also propose to provide means whereby, if the throttle is closed before the charge supplied to the accelerating well has been fed to the mixing passage, the balance of said charge is withdrawn from the well and will not be delivered to the mixing passage. I also propose to provide a suitable vent to prevent the trapping of air in the pump when the pump plunger is raised on the closing of the throttle.

Referring more particularly to the accompanying drawings, the invention is illustrated as applied to a standard type of carburetor comprising the usual float chamber, 10, from which motor fuel is supplied to a mixing passage or chamber 12 having an inlet portion 13 controlled by the choke valve 14, a discharge opening 15 controlled by a throttle valve 16, and a Venturi portion 17 positioned between the valves 14 and 16. Motor fuel is supplied through the adjustable needle valve 18 and a passage or duct 19 to a nozzle 20 projecting axially within the Venturi member. The fuel is received in an annular chamber 21 in the lower portion of the nozzle surrounding an air inlet tube 22 and rises around the tube 22 into a narrow annular passage between the tube 22 and a spaced enclosing tube 23, the upper end of the air tube communicating with said annular passage at the upper end of the surrounding tube 23 through openings 24. When the throttle valve 16 is open, or partly open, air is drawn through the tube 22 and openings 24 into the surrounding tube 23, in which it mingle with the fuel supplied thereto and passes therewith through openings 25 in the tube 23 into an outer sleeve 26 and through the upper open end of the sleeve 26 into the Venturi member 17. The quantity of air and fuel drawn through the nozzle 20 is governed by the opening of the throttle valve.

When the throttle valve 16 is closed, a small amount of motor fuel may, however, be supplied to the discharge end 15 of the carburetor, supplying sufficient fuel for slow speeds or for idling. This fuel is supplied through the duct 19 to an upright tube 28, the upper end of which opens into a slow speed jet chamber 30. When the throttle is closed and the engine is turning over, air is drawn through an adjustable inlet 31 into the chamber 30 and mixes with fuel sucked into the chamber 30 from the tube 28, said

mixture being delivered through one or both of the openings 32 leading from the chamber 30 into the discharge portion 15 of the mixing chamber above the throttle valve.

When the throttle valve 16 is opened, the fuel is normally supplied mainly or entirely through the nozzle 20 and the quantity supplied is proportional to the opening of the throttle. As the throttle is opened to speed up or accelerate the engine, there is a need for a richer fuel mixture during the period of time immediately after the throttle is opened, during which more power is required to overcome the inertia of the engine and driving mechanism as it speeds up, than during the steady running of the engine at high speeds, for which the fuel supply through the nozzle 20 is adjusted. Fuel to meet this additional temporary need and to facilitate rapid acceleration is supplied by the present invention by feeding to the mixing chamber a charge of fuel and distributing this charge over the period during which the additional power is required.

To supply this additional charge, a quantity of fuel is permitted to flow from the float chamber 10 through a narrow duct 33, Fig. 4, into a pump chamber 34 and fill the chamber 34 up to the bottom face of a plunger 35 movable vertically therein. The plunger 35 is urged upwardly by means of a spring 36 confined between the lower face of the plunger and a plug 37 closing the lower end of the pump chamber. The upward and downward movement of the plunger 35 is limited, and its position controlled, by means of a lever arm 38, rigidly mounted on a shaft 39, on which the throttle valve 16 is mounted, and having an arm 40 at right angles, against which the upper end of the plunger 35 is forced by the spring 36. The lever arm 38 is so mounted on the shaft 39 that it is in its uppermost position when the valve 16 is closed and that it has forced the plunger 35 to its lowermost position, against the action of the spring 36, when the valve is in its position of greatest opening, the plunger being forced downwardly in direct relation to the position of the throttle valve 16.

When the plunger is forced downwardly with an opening movement of the throttle 16, a small portion of the fuel in the chamber 34 is forced back through the opening 33 into the float chamber 10, but a much larger quantity is forced through a larger opening 42 into a well 43 extending upwardly from the level of the opening 42, parallel with the pump chamber 34. The well 43 is provided at its upper end with an opening 44 to the atmosphere which permits the escape of air as the fuel is forced into the lower portion of the well. A nozzle 46 is provided connecting the well 43 and the Venturi portion 17 of the suction

chamber 12 at a level slightly above the normal fuel level.

When the throttle valve, 16, is closed, the pump chamber 34 remains filled with fuel up to the lower face of the plunger 35 and the well 43 is filled up to the normal fuel level which is below the nozzle 46, no fuel being drawn into the suction chamber through this passage. When, however, the 10 throttle valve 16 is moved towards open position, the plunger 35 is depressed by the lever arm 38 and fuel is forced from the pump chamber, 34, into the well 43 raising the level of fuel in this well above the level 15 of the nozzle 46, a distance proportional to the movement of the valve 16 and the associated movement of the plunger 35. The fuel above the level of the nozzle, 46, then flows through the nozzle into the mixing 20 chamber, supplying the additional fuel required for speedy and effective acceleration and distributing its supply over a sufficient period of time to permit its effective utilization.

When the throttle valve 16 is moved towards closed position, the end of the lever arm 38 is raised proportionately and the plunger 35 forced upwardly by the spring 36, creating a suction which draws fuel from the well 43 and, at a slower rate, from the float chamber 10. If the closing of the throttle follows immediately upon its opening and before all of the additional fuel has passed from the well 43 through the nozzle 35 46 into the mixing chamber, the level of the fuel will fall below the level of the nozzle, 46, and the supply of this fuel to the mixing chamber will be cut off. If sufficient fuel is withdrawn from the well to lower its level below the normal fuel level, fuel will flow into the plunger chamber and well through the openings 33 and 42 until the level is restored.

It will be noted that the well, 43 is open 45 to the atmosphere through the vent, 44. This prevents the suction in the Venturi becoming effective through the nozzle, 46, to raise the fuel in well, 43, and draw it into the mixing chamber through said nozzle. This prevents the discharge of fuel through 50 said nozzle during the normal operation of the engine.

The closing movement of the throttle may, at times, be so extensive and rapid as to 55 draw air through the opening 44, well 43 and opening 42 into the pump chamber 34, and to trap such air below the plunger. This is objectionable as it causes irregular operation of the accelerating device. To 60 avoid this occurrence, which would interfere with the operation of the carburetor, a narrow air vent duct 47 is provided in the plunger 35 leading from the pump chamber to the atmosphere, through which any air 65 sucked into the plunger chamber would be

permitted to escape as the fuel rises in the chamber 34 when the throttle is closed. The duct 47 is so small and long that practically no fuel would be forced through it to the atmosphere and the open end of this duct is closed by the wall of the pump chamber as soon as the throttle has been opened a slight extent.

My present invention thus provides a means by which the demand for a temporary additional supply of fuel on the opening of the throttle valve is met and this additional supply of fuel is distributed through a sufficient period of time to permit its effective utilization. In this respect, my invention is a decided improvement over devices in which an accelerating pump injects an auxiliary charge of fuel directly into the mixing passage when the throttle valve is opened. Such devices provide an over-rich mixture at the instant of acceleration instead of spreading this charge over a period of time. Furthermore, by means of my invention, the wasting of fuel is prevented because, if the throttle valve is moved toward closed position 90 after having been opened, the auxiliary charge is withdrawn from the well and returned to the fuel supply chamber.

As changes of construction may be made within the scope of my invention, I desire 95 that all matter contained in the above description or shown in the accompanying drawings shall be interpreted as illustrative and not in a limiting sense.

Having thus described my invention, what 100 I claim as new and useful and desire to secure by Letters Patent is:

1. A carburetor comprising a mixing passage, a fuel supply chamber, a throttle valve, a well having a discharge opening to said passage, a plunger chamber having a small opening from said fuel supply chamber and a larger opening to said distributing well, a plunger in said plunger chamber, a spring confined between the bottom of said plunger and the bottom of the plunger chamber, said plunger having an air vent passage leading from said plunger chamber to the atmosphere closed by the wall of the chamber as the plunger is depressed, and means for depressing said plunger in said chamber against the pressure of said spring as said throttle valve is moved towards open position.

2. A carburetor comprising a mixing passage, a fuel supply chamber, a throttle valve, a well having a discharge opening to said passage above the normal fuel level and open to the atmosphere at its upper end, a plunger chamber having a small opening from said fuel supply chamber and a larger opening to said well, a plunger in said plunger chamber having a vent leading from said plunger chamber to the atmosphere closed as the plunger is depressed,

and means controlled by said throttle valve to move said plunger in and out of said plunger chamber as said valve moves towards open and closed positions, respectively.

5 3. A carburetor comprising a mixing passage, a throttle valve therein, means for supplying fuel and air to said passage, a pump for delivering an auxiliary charge of fuel to 10 said passage comprising a plunger chamber, a plunger actuated by opening movement of the throttle valve, and means including an opening in said plunger for permitting the escape of air from said chamber when the throttle valve is in closed position, said last 15 mentioned means being closed by the movement of said plunger.

4. A carburetor comprising a mixing passage including a Venturi tube; a throttle 20 valve; a well having a discharge opening at the restricted portion of said Venturi tube; a plunger chamber having an unobstructed passage of larger dimensions to said well and a passage of smaller dimensions to a source of fuel; a plunger in said 25 plunger chamber; means actuated by said throttle valve for forcing said plunger into said plunger chamber as said throttle valve is moved in an opening direction; means 30 including an opening in said plunger for permitting the escape of air from said chamber and adapted to be closed by the wall of the chamber as said plunger is depressed; and means for withdrawing said plunger as 35 said throttle valve is moved to a closing direction.

5. A carburetor comprising a mixing passage; a fuel supply chamber; a throttle valve; a well having a discharge opening to 40 said passage; a plunger chamber having an opening from said fuel supply chamber and an opening to said distributing well; a plunger in said plunger chamber; means for depressing said plunger in said chamber as 45 said throttle valve is moved towards open position, said plunger having an air vent passage to the atmosphere adapted to be closed by the wall of the chamber as the plunger is depressed.

6. A carburetor comprising a mixing passage; a fuel supply chamber; a throttle valve; a well having a discharge opening to said passage above the normal fuel level and open to the atmosphere at its upper end; 55 a plunger chamber having an opening from said fuel supply chamber and an opening to said well; a plunger in said plunger chamber having a vent to the atmosphere adapted to be closed as the plunger is depressed; and 60 means controlled by said throttle valve to move said plunger in and out of said plunger chamber as said valve moves towards open and closed positions, respectively.

65 7. A carburetor comprising a mixing pas-

sage; a fuel supply chamber; a throttle valve; a well having a discharge opening to said passage; a plunger chamber having a small opening from said fuel supply chamber and a larger opening to said well; a 70 plunger in said plunger chamber; a spring confined between the bottom of said plunger and the bottom of the plunger chamber; and means for depressing said plunger in said chamber against the pressure of said spring as said throttle valve is moved towards open position, said well and passage between the plunger chamber and well forming an unobstructed conduit to the well discharge passage, said plunger having an 75 air vent passage adapted to be closed by the wall of the chamber as the plunger is depressed.

In testimony whereof, I affix my signature.

CHARLES W. McKINLEY.
